(57) **CLAIM**

We claim the ornamental design for a device for storing children's artwork, as shown and described.

DESCRIPTION

FIG. 1 is a perspective view of a device for storing children's artwork, showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a top view thereof, shown unassembled.

The broken lines in the drawings depict unclaimed environmental subject matter.
